UNITED STATES PATENT OFFICE

EDWIN S. MIX, OF ROCHESTER, NEW YORK, ASSIGNOR TO HICKOK MANUFACTURING COMPANY, INC., OF ROCHESTER, NEW YORK, A CORPORATION OF NEW YORK

STRAP EDGE FINISHING MACHINE

Application filed June 6, 1928. Serial No. 283,397.

The present invention relates to strap edge finishing machines, and an object of the invention is to provide a simple, inexpensive and effective construction for coloring and 5 burnishing the opposite edges of leather straps such, for instance, as those employed in making leather belts for personal wear. Another object of the invention is to provide a novel means for moving a belt as it 10 is being acted upon by a coloring and/or burnishing mechanism. Still another object of the invention is to provide an improved coloring mechanism for coloring the opposite edges of a strip of material. A 15 further object of the invention is to provide a novel means for burnishing an edge of a strip of material.

To these and other ends, the invention consists of certain parts and combinations 20 of parts, all of which will be hereinafter described: the novel features being pointed out in the appended claims.

In the drawings:

Fig. 1 is a plan view of a machine constructed in accordance with this invention;

Fig. 2 is a fragmentary view partially in section illustrating the inking mechanism;

Fig. 3 is a fragmentary view in plan illustrating the burnishing mechanism;

Fig. 4 is a side view of the machine with parts broken away and parts in section;

Fig. 5 is a sectional view through the intake guiding means on the line 5—5, Fig. 4;

Fig. 6 is a fragmentary vertical sectional view through the burnishing means;

Fig. 7 is a vertical section through the machine;

Fig. 8 is a fragmentary view partially in section illustrating the rear feeding mechanism;

Fig. 9 is a fragmentary view showing the driving mechanism for the kick-off means; and

Fig. 10 is a detail view showing the driving mechanism for the burnishing means.

In the illustrated embodiment of the invention, there is employed a bed plate 1 at the forward end of which is a feeding table 2 on which the material to be operated on is 50 placed.

Supported at the forward part of the main bed plate 1 is an intake guide for the strips to be operated upon, comprising, in this instance, a post 3 supporting a guide plate 4 at its upper end, said guide plate having 55 transverse guide ways 5 in its upper surface receiving strip-guiding blocks 6 which through clamps 7 are held in any desired position on the guide plate 4. These strip-guiding blocks 6 have their adjacent forward portion bevelled at 8 so as to facilitate the entrance of the strip into the guide-ways 9 formed in the opposed sides of the blocks 6.

After passing from the intake guiding 65 means each strip is engaged by a feeding mechanism comprising, in this instance, two rollers 10 and 11 arranged one above the other. The roller 10 is secured to a shaft 12 which is supported on the bed plate 1 by three bearing blocks 13, 14 and 15. The bearing blocks 13 and 14 project above the bearing block 15 and are connected by a top piece 16. These bearing blocks 13 and 14 also support, above the roller 10, the roller 11 which has its shaft 17 turning in the movable bearings 18, the roller 11 being normally held toward the roller 10 by springs 19 pressing against the moving bearings 18. The rollers 10 and 11 may be driven together with adjacent peripheral portions 70 moving in the same directions by means of transmission gears 20 and 21 provided respectively on the shafts 12 and 17.

The driving of the feeding rollers 10 and 11, as well as the other mechanisms to be hereinafter described, may be effected by an electric motor 22 supported on a motor bed 23 and having a shaft 24 connected through 75 gearings in the casing 25 to a shaft 26. This shaft 26 which is supported by the casing 25 has a gear 27 on the exterior of the casing meshing with a gear 28 on the shaft 12, so as to drive the feed rollers 10 and 11.

From the feed rollers 10 and 11 the strips 80 are fed to another guiding means which in this instance comprises two guide bars 29 and 30, the former being rigidly supported on two posts 31 on the bed plate 1, and the latter being adjustable toward and from the 85

guide bar 29. In order to adjust the guide bar 30, the latter may have two internally threaded sleeves 32 projected on its upper side and engaged by externally threaded screws 33 which are rotatably mounted in its supporting member 34, the latter having its forward end secured by a screw 35 to the top piece 16 and being also secured at 36 to a top piece 37 connecting the upper end 10 with two bearings 13 and 14 projected upwardly from the bed plate 1 adjacent the rear ends of the guide bars. The guide space between the two guide bars 29 and 30 opens laterally on both sides through the 15 greater portion of the length of the bar, but near the middle portion of the bars this space is closed preferably by an inverted channel member 39 which straddles the two bars and rests on the upper guide bar 30 20 being adjustable longitudinally of the guide bar 30 through a bolt 40 anchored in the guide bar 30 and extending through a slot 41 in the inverted channel member 39. With the end of insuring the passage of the 25 strip from the feeding rollers 10 and 11 to the guiding means, the roller 11 is provided with a central peripheral groove 42 and into this groove extends a stripper 43 from the forward end of the guide member 30. 30 While the strip is travelling along the guiding bars 29 and 30 its edges may be subjected to an inking or coloring mechanism. In this instance this inking or coloring mechanism comprises two ink applying 35 rollers 44 and 45 having soft faced peripheries and operating in a single horizontal plane and upon opposite sides of the guiding means, the guiding bars 29 and 30 being recessed at 46 on opposite sides thereof so that the rollers may move transversely of their 40 axes of rotation and in the plane of the travelling strip in order to exert pressure on the edge of a strip during the application of the ink or coloring matter. So that the 45 rollers may have this relative movement toward and from the edges of the strip and may be held with even pressure against the strip, the rollers may be mounted to turn on posts 47 which are supported by blocks 50 arranged on a shaft 49 and held against 55 turning on said shaft by pins 50 projecting upwardly from the bed plate 1 and entering slots or guides 51 formed in the blocks 48. This arrangement permits the blocks 48 to move longitudinally of the shaft but at the 60 same time it holds the blocks 48 against turning with the shaft 49. The application of the ink or coloring to the ink applying wheels 44 and 45 as well as the driving of 65 said wheels is effected by two discs 52 and 53, these discs are mounted on the shaft 49, being secured to the shaft in such a manner that they will turn with the shaft 49 but may move axially of the shaft. The discs 65 are held with yielding pressure toward the

wheels 44 and 45 by helical springs 54 which surround the shaft 49 and abut the discs 52 and 53 as well as bearing blocks 55 extending upwardly from the bed plate 1 and serving to support the shaft 49. The driving of the shaft 49 may be effected through a gear 56 on said shaft meshing with a gear 57 on the shaft 12. Each of the discs 52 and 53 operate in one of two inking or coloring receptacles 58 which are situated beneath the discs 52 and 53. 70

The ready removal of the coloring receptacles may be effected by providing pockets or depressions 59 beneath them. Each depression is wide enough to permit the receptacle to be dropped therein and it does not extend to the rear end of the receptacle when the latter is in operative position so that the rear end rests upon the main surface of the bed plate. At its forward end each receptacle has a leg 60 which will cooperate with the feeding table 2 to hold the forward end of the receptacle in a raised position. By pulling forwardly on a receptacle, its rear end will slide off the main surface of the bed plate 1 and drop into the pocket or recess 59 so that its upper edge will be below the lowermost portion of the discs 52 or 53. The receptacle may now be removed from the machine without any interference with the operative parts of such a machine. 80

After the strip passes from the inking mechanism and while it is travelling on the guideway 29 or 30, it is operated upon by a burnishing mechanism which comprises, in this instance, two rotary burnishing wheels or members 61 operating in a horizontal plane and also on opposite sides on the guiding means the latter being cut away at 62 on opposite sides to permit the burnishing members to engage the strip. Each burnishing member is formed with a peripheral groove 63 the walls of which are toothed or serrated at 64. These teeth have a novel action on the leather and tend to beat the loose fibers into compact relation with the main body of the leather. Any suitable means may be employed for supporting these burnishing wheels or members 61. 105 In this instance, the two members are secured each to one of two shafts 65 and 66 which are journaled in swinging blocks 67 and 68 pivoted at 69 and 70 to the bed plate 1. The bed plate is provided with slots 71 and 72 through which the shafts 65 and 66 respectively extend and beneath the bed plate, the shafts 65 and 66 are provided with pulleys 73 and 74 respectively. These two pulleys 73 and 74 are geared together so that they may rotate in the same direction, in order that the adjacent peripheral portions of the two burnishers 61 may move in opposite directions the adjacent peripheral portion of one roller moving in a direc- 115 120 125 130

tion opposite to the direction of the movement of the strap under the feeding means and the adjacent peripheral of the other roller moving in the direction of the movement of the strap but at greater speed than the strap. This is effected by a belt 75 passing about both pulleys 73 and 74 and also about an idler pulley 76. This idler pulley is supported upon a swinging arm 77 acted upon by a spring 78 which causes the idler pulley 76 to act as a tension take-up device and permits the pulleys 73 and 74 to partake of relative movement toward and from each other as well as the yielding movement between the burnishers 61, while at the same time holding the burnishers toward the edges of the strap. A stop 79 in the form of an adjustable screw may be mounted in the swinging member 67 and be adapted to cooperate with the swinging member 68 to limit the movement of the burnishers toward each other, the stop being adjustable to accommodate straps of different widths between the burnishers 61. An adjustable stop 80 mounted on a post 81 on the bed plate 1 limits the movement of the swinging members 68 away from the strap. The turning of the burnisher may be effected through a belt 82 which passes about a pulley 83 on a shaft 24 of the motor and also about a pulley 84 on the shaft 66.

After a strap passes from the burnishing means, it is again subjected to a feeding action effected, in this instance, through two rear feeding rolls 10 and 11 which are identical in construction with the primary feeding rolls 10 and 11 hereinbefore described and which are driven in the same manner except that the shaft 12 of the lower roll 40 connects by a sprocket chain 85 with the shaft 12 of the other lower roll 10. These rolls 10 and 11 of the secondary mechanism are supported on the bearings 38 before mentioned to which the bar 34 is secured.

After leaving the secondary feeding rolls, a strap passes to a secondary guide comprising, in this instance, a single post 86 supported on the bed plate 1 and carrying a guide piece 87 at its upper end. Above this guide piece is a guide piece 88 which preferably is resiliently supported and to this end has a stem 89 projecting upwardly therefrom and provided with a reduced upward extension 90 formed with screw threads 91 at its upper end. This upward extension may be guided in a bracket 92 formed integrally with the bar 34, a spring 93 being positioned about the reduced portion and abutting the bracket and a nut 94 being arranged on the screw threaded portion 91 so as to adjust the position of the guide piece 88. The guide piece 88 may have a stripper 95 projecting forwardly therefrom to enter the groove 42 formed

in the roll 11 of the secondary feeding device.

While upon this secondary guide 87 and 88, the strap may be subjected to a varnishing at its edges and this may be effected through a varnishing mechanism identical with the inking or coloring mechanism hereinbefore described, with the exception that for the ink containing receptacle 58 is substituted a single receptacle 58^a, supported on the bed plate 1. This varnishing mechanism is driven from the shaft 12 of the secondary feeding mechanism and acts to color the edge of a strap after the burnishing.

After passing the varnishing mechanism, a strap is ejected from the machine preferably through the means of a roller 96 supported by a swinging frame 97 which turns on the shaft 17 of the upper wheel 11 of the secondary feeding mechanism. This wheel 96 cooperates with the lower guide member 87 beyond the guide 88 and operates at a higher speed than the roller 11, its operation being preferably effected through a belt 98 which passes about a small pulley 99 on the shaft 17 and about a larger pulley 100 on a shaft 101 of the roller 96. This roller 96 may be kept in a clean condition by a sponge 102 supported by a swinging frame 103 mounted on the swinging frame 97. The roller 96 gives to the strap its final kick off so as to project the strap preferably upon the endless carrier 104 supported in rear of the bed frame 1 by two pulleys 105 and 106. The pulley 106 may be driven from the motor 22 through a worm wheel 107 meshing with a worm 108 on the shaft 26. The worm wheel 107 is mounted on a shaft 109 which has a gear 110 thereon meshing with a gear 111 on the shaft of the pulley 106. The speed of the endless carrier or belt 104 is such that the straps are delivered to the belt to lie in parallel relation thereon out of engagement with each other so that they may have an opportunity to dry before being brought into contact with each other or being handled.

The operation of this invention will be understood from the foregoing but it may be summarized as follows: Straps or belts are delivered endwise into the intake guides 6 until they are engaged by the primary feeding rollers 11 which then project them between the two guide members 29 and 30 where they are first acted upon by the primary or preliminary inking mechanism formed by the two rollers 44 and 45. The straps are then passed to the burnishing rollers 61 and then to the secondary feeding rollers 10 and 11 which carry them to the varnishing mechanism and to the ejecting roller 96 which deposits them upon the endless feed belt 104.

What I claim as my invention and desire to secure by Letters Patent is:

1. In a strap edge finishing machine, an intake guide comprising a guide plate formed with a guideway extending transversely of the line of travel of the strap, on the guide, two guide blocks having opposed grooved sides and beveled ends leading to said grooved sides, and means for adjusting the blocks relatively to each other on the guideway. 70
2. In a strap edge finishing machine, a feeding mechanism comprising two spaced pairs of feeding rolls, two guide bars extending between the rolls, and means for adjusting one of the bars toward and from the other to accommodate straps of different thicknesses. 75
3. In a strap edge finishing machine, a feeding mechanism comprising two spaced pairs of feeding rolls, two guide bars extending between the rolls, and means for adjusting one of the bars toward and from the other to accommodate straps of different thicknesses, and an inverted channel member straddling one of said bars and having its sides arranged on opposite sides of the other bars. 80
4. In a strap edge finishing machine a base plate, two bearing frames extending upwardly from the base plate in spaced relation to each other, a pair of rollers mounted on each bearing frame, two strap guiding bars extending between the two pairs of rollers, one of said guide bars being supported from the bed plate, a bar extending between the two bearing frames, and means adjustably supporting the other guide bar from the connecting bar. 85
5. In a strap edge finishing machine, the combination with means for feeding straps of an inking mechanism for cooperating with the opposite edges of straps moved by the feeding means, said inking mechanism comprising two inking rollers cooperating with the opposite edges of the straps, a shaft, two ink feeding rollers mounted on said shaft and engaging and driving the inking rollers, means for driving the shaft to drive the ink feeding rollers, and means for supplying ink to the ink feeding rollers. 90
6. In a strap edge finishing machine, the combination with means for feeding straps, of means for inking an edge of a strap moved by the feeding means comprising an inking roller cooperating with said edge and movable toward and from said edge, an ink feeding roller cooperating with the periphery of the inking roller and driving said roller, means yieldingly holding the ink feeding roller in engagement with the feeding roller to hold the latter toward the strap edge, means for driving the ink feeding roller and means for supplying the ink with the ink feeding roller. 105
7. In a strap edge finishing machine the combination with means for feeding straps, of an inking roller operating in the plane of the strap moved by the feeding means and having its edge cooperating with the edge of the strap, and an ink feeding roller operating in a vertical plane at an angle to the plane of operation of the inking roller and engaged on one side by the periphery of the inking roller, the periphery of the ink feeding roller being beveled in a direction to conduct surplus ink away from the periphery of the inking roller. 110
8. In a strap edge finishing machine, the combination with means for feeding straps, of an inking roller operating in the plane of the strap fed by the feeding means and having its periphery engaging an edge of the strap, a movable support for said inking roller, a shaft on which said support is movable toward and from the edge of the strap, an ink feeding roller mounted on the shaft to turn therewith and having its side engaging the periphery of the inking roller, yielding means acting on said ink feeding roller to hold it toward the inking roller, and means for supplying ink to the ink feeding roller. 115
9. In a strap edge finishing machine, the combination with means for feeding straps, of a bed on which said feeding means is mounted, having a pocket, an inking roller cooperating with a strap moved by the feeding means, an ink feeding roller for the inking roller arranged above the pocket in the bed plate, an ink receptacle supported below the roller and on the bed above the pocket, said receptacle being movable on the bed plate to drop into the pocket so that it may be withdrawn from the bed without interfering with the ink feeding roller. 120
10. In a strap edge finishing machine, the combination with means for feeding the strap, of two inking rolls mounted to turn about upright axes on opposite sides of the straps fed by the feeding means to cooperate with opposite edges of the straps, a shaft lying to one side of the plane of the straps fed by the feeding means, two supports one for each of the inking rollers movable on the shaft, means for holding the supports against turning on the shaft, two ink feeding rollers mounted to turn with the shaft but to move axially thereof, the sides of said ink feeding rollers cooperating with the peripheries of the ink feeding rollers, and spring means acting on the two ink feeding rollers to hold the latter in engagement with the inking rollers and the inking rollers in engagement with the opposite edges of the straps. 125
11. In a strap edge finishing machine, the combination with means for feeding a strap, of guiding means for supporting the opposite faces of said strap, two rotary burnishers for cooperating with opposite edges 130

of the strap fed by the feeding means and while it is supported by the guiding means, means supporting said rotary burnishers so that they will be moved toward and from 5 opposite edges of the belt, and a resilient means acting on said burnisher supporting means to hold the burnisher with yielding pressure toward the opposite edges of the straps.

10 12. In a strap edge finishing machine, the combination with means for feeding a strap, of guiding means for supporting the opposite faces of said strap, two rotary burnishers for cooperating with opposite edges 15 of the strap fed by the feeding means and while it is supported by the guiding means, means supporting said rotary burnishers so that they will be moved toward and from opposite edges of the belt, and a resilient 20 means acting on said burnisher supporting means to hold the burnishers with yielding pressure toward the opposite edges of the straps, and an adjustable stop carried by one of said supporting means and engaging 25 the other to limit the movement of the burnishers toward each other.

13. In a strap edge finishing machine, the combination with means for feeding a strap, of two rotary burnishers cooperating with 30 opposite edges of said strap fed by the feeding means, and means for driving the burnishers so that one has the portion of the periphery engaging the strap moving in the direction of movement of the strap, and the 35 other has that portion of the periphery engaging the strap moving in the direction opposite the movement of the strap, but at a greater speed than the strap.

14. In a strap edge finishing machine, the 40 combination with means for feeding a strap, of two rotary burnishers cooperating with opposite edges of the strap, two movable carriers on which the burnishers turn, two pulleys moving with the carriers, one on the 45 shaft of each of the burnishers, an idler pulley, yielding supporting means for the idler pulley, a belt passed about the pulleys, and means for driving one of the pulleys to transmit motion to the burnishers.
